REMOTE CONTROL APPARATUS

Application filed January 31, 1929. Serial No. 336,413.

My invention relates to remote control apparatus, and particularly to apparatus for safely controlling traffic governing devices such as railway switches and signals from a 5 distant point.

One feature of my invention is the provision of means including non-coded currents of different characteristics for separately controlling a switch and a signal and two approach indications over one pair of conductors.

I will describe one form of apparatus embodying my invention, and will then point out the novel features thereof in claims.

15 The accompanying drawing is a diagrammatic view showing one form of apparatus embodying my invention.

Referring to the drawing, the reference characters 1 and 1¹ designate the rails of a 20 stretch X of railway track connected by means of a switch F with a siding Y. Switch F, in its normal position as shown in the drawing, directs traffic over stretch X only, and, in its reverse position, directs traffic over 25 stretch X to or from siding Y.

The rails of stretch X are divided by insulated joints 2 to form an approach track section A—B west of switch F and which as shown in the drawing is to the left, and 30 section C—D east of switch F and which as shown in the drawing is to the right. Each of these track sections is provided with a track circuit, which is supplied with current by a battery 3 connected across the rails adjacent one end of the section. The track circuit for section A—B includes the track relay G¹, and the track circuit for section C—D includes the track relay G². Slow releasing 35 repeater relays, designated by the reference characters g¹ and g², are controlled respectively by front contacts of track relays G¹ and G².

40 Signals designated by the reference characters S¹, S², S³ and S⁴ govern movements of traffic over switch F, signals S² and S³ governing over switch F in its normal position, and signals S¹ and S⁴ governing over switch F in its reverse position. Each of these signals as here shown is of the semaphore type.

45 50 As indicated in the drawing, switch F is

operated by a motor M comprising an armature 5 and a field winding 6, which is controlled in any suitable manner by the polarized relay E. An example of such control is shown in Fig. 1 of the drawings included 55 in my co-pending application filed May 19, 1928, Serial No. 279,086 for remote controlling apparatus, in which motor M is controlled by a polarized relay R and a circuit controller a.

A polarized signal relay H, having windings 51 and 52, controls signals S¹, S², S³ and S⁴ in accordance with the position of switch F. Windings 52 is continuously supplied with alternating current from a suitable 60 source over wires *a* and *o*.

Switch control relay E and signal control relay H are controlled over a pair of conductors 11 and 17 by manually operable levers V¹ and V² respectively, which may be included 70 in a group of such levers at some central location, such as a train despatcher's office. Lever V¹ has a normal position N and a reverse position R, and is provided with contacts 8 and 44 which are closed only while lever V¹ is in its N or its R position respectively. Lever V² has a normal position N, a reverse position to the left designated by the reference L, and a reverse position to the right designated by the reference R. Lever V² is 75 provided with contacts 22, 30 and 32 which are closed only while lever V² occupies its L, N, or R positions respectively.

Indication of the approach of a train in sections A—B or C—D is provided by lamps 80 e² and e¹ which are controlled by relays K² and K¹ respectively. A transformer T supplies current through the contacts of lever V² for operating relays K² and H. The primary winding 18 of transformer T is continuously supplied with alternating current from the wires *a* and *o*. The secondary side of transformer T is provided with two windings 90 19 and 20 having a common terminal 76. Batteries Q¹ and Q² supply direct current 95 through the contacts of lever V¹ for operating relays K¹ and E. Condensers 25 and 26 prevent direct current, from batteries Q¹ and Q², from reaching relays K² and H. Impedance winding 13 and the winding of relay K¹ 100

have sufficient reactance to prevent more than a small amount of alternating current from flowing through relays E and K¹ respectively.

5 A battery Q³, located adjacent switch F, supplies current for operating repeater relays g¹ and g², and signals S¹, S², S³ and S⁴.

Having thus described, in general, the arrangement and location of the various parts comprising my invention, I will now proceed to explain the operation of the apparatus.

10 As shown in the drawing, all parts are in their normal condition, that is, track sections A—B and C—D are unoccupied, levers V¹ and V² are in their normal or N position, switch F is in its normal position, and each of the signals S¹, S², S³ and S⁴ indicates "stop".

15 With track sections A—B and C—D unoccupied, relays G¹ and G² are energized. 20 Relays g¹ and g² are energized by their control circuits including battery Q³ and passing through contacts 61 and 63 of relays G¹ and G² respectively.

25 With lever V¹ in its N position, relay E is energized in its normal direction by current flowing from battery Q², through wire 7, contact 8 of lever V¹, wire 9, winding of relay K¹, wires 10, 11 and 12, impedance 13, wire 14, winding of relay E, and wires 15, 16 and 17 back to battery Q². The current flowing in this circuit, although of sufficient magnitude to cause relay E to close its front contacts, is not great enough to cause relay K¹ to close its contact 74 which is therefore open.

30 With lever V² in its N position, a circuit is completed passing from secondary winding 20 of transformer T, through wire 29, contact 30 of lever V², wire 23, winding of relay K², wire 24, condenser 25, wire 11, condenser 26, wire 27, winding 51 of relay H, and wires 28, 17 and 73 to terminal 76 of transformer T. The current flowing in this circuit is, however, of insufficient magnitude to operate 45 either relay H or K².

Since the front contacts of relays K¹ and K² are open, indicator lamps e¹ and e² are unlighted.

50 I will assume that an approaching eastbound train de-energizes relay G¹, which then opens its front contact 61 in the circuit of relay g¹, and closes its back contact 58 completing a branch path around winding 51 in the circuit previously traced for relay H. 55 This branch path passes from condenser 26, through wire 56, contact 57 of relay g¹, contact 58 of relay G¹, and wire 59 to wire 28. Relay g¹, being of a slow releasing type, retains its contact 57 in the closed position for 60 a short period of time after contact 58 of relay G¹ has been closed. Meanwhile, the branch path just traced permits sufficient current to flow to cause relay K² to close its front contact 70. Indicator lamp e² then becomes 65 lighted by its circuit passing from battery

Q², through wires 68 and 69, contact 70, wire 71, lamp e², and wires 72 and 73 back to battery Q². As soon as relay g¹ opens its front contact 57, thereby opening the branch path around winding 51 of relay H, the current flowing through relay K² is so reduced that contact 70 again opens, thus extinguishing lamp e².

70 If, on the other hand, when all parts are again in their normal condition as previously described, an approaching westbound train de-energizes relay G², the circuit for relay g² is opened at contact 63 of relay G², and a branch path around relay E is completed through back contact 54 of relay G². This branch path passes from wire 14, through wire 53, contact 54, and contact 55 of relay g² to wire 16. By the completion of this branch path, the resistance in series with relay K¹ is so reduced as to permit sufficient current to flow to cause relay K¹ to close its front contact 74, thereby completing the lighting circuit of lamp e¹. This lighting circuit passes from battery Q², through wire 68, contact 74, wire 75, lamp e¹, and wires 72 and 73 back to battery Q². Lamp e¹ is thus lighted, indicating to the despatcher that an approaching train has entered section C—D.

75 I will now assume that all parts are again in their normal condition as previously described, and that the despatcher desires to clear signal S² for an eastbound train to move over switch F. He accordingly operates lever V² to its R position, thus completing, through contact 32 of lever V², a circuit for relay H passing from secondary winding 20 of transformer T, through wire 31, contact 32, wire 23, winding of relay K², wire 24, condenser 25, wire 11, condenser 26, wire 27, 80 winding 51 of relay H, and wires 28, 17 and 73 to terminal 76 of transformer T. Sufficient current then flows to cause relay H to close its contacts to the left position, but not to cause relay K² to close its front contact. 85 Relay H, upon closing its contacts to the left position, completes, through its contact 40^a, the operating circuit for signal S² passing from battery Q³, through wires 33 and 34, front contact 35 of relay E, normal contact 36^a of relay E, wire 37, contact 38 of circuit controller a which is operated by switch F, wire 39, contact 40^a of relay H, wire 41, operating mechanism of signal S², and wires 65, 66 and 67 back to battery Q³.

90 Signal S² is then operated to its "proceed" position. If, now, an approaching eastbound train de-energizes relay G¹, the branch path around winding 51 of relay H becomes closed as previously described, causing relay K² to close its contact 70 and lamp e² to become lighted by the circuit already traced.

95 I will next assume that all parts are again in their normal condition and that the despatcher desires to reverse switch F for a 100

train to move from stretch X to siding Y. He accordingly operates lever V¹ to its R position, thus completing a circuit by which current flows in the reverse direction through the winding of relay E. This circuit passes from battery Q¹, through wires 17, 16 and 15, winding of relay E, wire 14, impedance 13, wires 12, 11 and 10, winding of relay K¹, wire 9, contact 44 of lever V¹, and wire 43 back to battery Q¹. Relay E then closes its polar contacts in the reverse position, causing switch F to be operated to its reverse position.

If, then, the despatcher desires to clear signal S⁴, he will operate lever V² to its L position, sending current through winding 51 of relay H in a reverse direction with respect to the current flowing through winding 52. The circuit, by which this current of reverse relative polarity travels, passes from terminal 76 of transformer T, through wires 73, 17, and 28, winding 51 of relay H, wire 27, condenser 26, wire 11, condenser 25, wire 24, winding of relay K², wire 23, contact 22 of lever V², and wire 21 to secondary winding 19 of transformer T. Relay H then closes its contacts toward the right, completing the operating circuit for signal S⁴ passing from battery Q³, through wires 33 and 34, front contact 35 of relay E, reverse contact 36^b of relay E, wire 45, contact 46—46^a of circuit controller a and which is now closed on account of switch F being in its reverse position, wire 47, contact 48^b of relay H, wire 50, operating mechanism of signal S⁴, and wires 66 and 67 back to battery Q³. The arm of signal S⁴ is then operated to its "proceed" position. If now a train de-energizes relay G², lamp e¹ will become lighted as previously described.

From the foregoing descriptions for typical traffic moves, the operation of the apparatus shown in the accompanying drawing will be readily understood for other traffic moves.

Although I have herein shown and described only one form of remote control apparatus embodying my invention, it is understood that various changes and modifications may be made therein within the scope of the appended claims without departing from the spirit and scope of my invention.

Having thus described my invention, what I claim is:

1. In combination with a railway switch and a signal for governing the movement of traffic over said switch, a first manually operable lever, a second manually operable lever, a pair of line wires extending from a point adjacent said levers to a point adjacent said switch, a first source of current, a second source for supplying current of a different character than current supplied by said first source, means for controlling the operation of said switch by current from said first source supplied to said line wires by said first lever, means for controlling said signal by current from said second source supplied to said line wires by said second lever, two track sections adjacent said switch, a track circuit for each of said sections each including a track relay, a first approach indication means controlled through a contact of the first of said track relays by current from said first source supplied to said line wires by said first lever, and a second approach indication means controlled through a contact of the second of said track relays by current from said second source supplied to said line wires by said second lever. 70

2. In combination with a railway switch and a signal for governing the movement of traffic over said switch, a first manually operable lever, a second manually operable lever, a pair of line wires extending from a point adjacent said levers to a point adjacent said switch, a first source for supplying direct current, a second source for supplying alternating current, a polarized first control relay responsive to direct current from said first source, a second control relay responsive to alternating current from said second source, a first and a second approach track section for said switch, a track circuit for each of said sections each including a track relay, a slow releasing repeater relay for each of said track relays each controlled by a front contact of its track relay, a first indication relay responsive to direct current, a second indication relay responsive to alternating current, a circuit including said first control relay and said first indication relay as well as said line wires in series and an impedance between said first control relay and one of said line wires having high reactance to alternating current but only low resistance to direct current, means for supplying said circuit with current of normal or reverse polarity from said first source by said first lever and of sufficient magnitude to operate said first control relay 80

90

95

100

105

110

115

120

125

130

said second control relay in said circuit including a back contact of the second track relay and a front contact of its repeater relay, which branch path when closed permits sufficient current to flow to operate said second indication relay, indication means controlled by said first indication relay, indication means controlled by said second indication relay, means for controlling the operation of said switch by said first control relay, and means for controlling the operation of said signal by said second control relay.

In testimony whereof I affix my signature.

CHARLES W. BELL.
